(57) **CLAIM**

The ornamental design for a dial member for binocular or the like, as shown and described.

DESCRIPTION

FIG. 1 is a perspective view from upper and front side of a dial member showing our new design;

FIG. 2 is a perspective view from upper, front and right side thereof;

FIG. 3 is a perspective view from lower, rear and left side thereof;

FIG. 4 is a front view thereof;

FIG. 5 is a rear view thereof;

FIG. 6 is a top plan view thereof;

FIG. 7 is a bottom plan view thereof;

FIG. 8 is a right side view thereof;

FIG. 9 is a left side view thereof;

FIG. 10 is a perspective view from the upper and front side of the dial member shown in an alterante state of use;

FIG. 11 is a perspective view from upper, front and left side view thereof;

FIG. 12 is a front view thereof;

FIG. 13 is a rear view thereof;

FIG. 14 is a top plan view thereof;

FIG. 15 is a bottom plan view thereof;

FIG. 16 is a right side view thereof;

FIG. 17 is a left side view thereof;

FIG. 18 is a right side view of a dial member of the binoculars; and,

FIG. 19 is a left side view of the dial member of the binoculars.

The dash-dash broken lines showing binoculars are for environmental purposes and form no part of the claimed
